UNITED STATES PATENT OFFICE.

JOSIAH E. REID AND CHARLES L. NEIN, OF NEW YORK, N. Y., ASSIGNEES TO INTER-NATIONAL MOTOR COMPANY, OF NEW YORK, N. Y., A CORPORATION OF DELAWARE.

HOISTING MECHANISM FOR DUMP TRUCKS.

Application filed September 12, 1923. Serial No. 662,297.

In a co-pending application Serial No. 662,296 filed by the present applicants on September 12, 1923, there is shown, described and claimed broadly a mechanically operated hoisting mechanism for dump bodies of motor vehicles which is characterized by the employment of lifting screws supported on a vehicle frame with capacity to move angularly with respect thereto during the raising and lowering of the body. The particular embodiment of the invention illustrated in said co-pending case showed two lifting screws mounted in an integral saddle or cradle which itself is pivotally mounted through trunnions in the side frame members of the vehicle chassis. This saddle or cradle, extending transversely of the chassis occupies space which, under some circumstances, might be required for the accommodation of some necessary part or parts of the vehicle drive. That is to say, when a chain drive is employed, for instance, the chassis is clear between the side frame members and ample space is afforded for the said cradle or trunnion, but when a propeller shaft extends longitudinally under the chassis frame ample clearance therefor is necessary. The present invention relates to a hoisting mechanism which operates on the principle of that described in said co-pending application but to a different embodiment wherein there is employed, in place of the single supporting saddle or cradle for the lifting screws, separate supporting cradles or saddles therefor which may be so spaced with respect to one another as to afford additional space or clearance, as for a longitudinally extending propeller shaft. Still another object of the invention is to mount the lifting rods in independent cradles with capacity for angular movement not only with respect to the vehicle frame during the raising and lowering of the body but also with respect to one another so that they may conform to weaving of the frame or body and adapt themselves to relative movements impressed by other stresses. In accordance with the invention the same principle described and claimed in said co-pending case is employed but the revolving nuts for actuating the lifting rods are mounted within casings which have their own supporting trunnions at opposite sides, the remote trunnions being journaled in brackets carried by the side frame members

of the vehicle and the proximate trunnions being journaled in longitudinal supports mounted between the side frame members. The gearing for actuating the jack shafts by which the nuts are revolved may be enclosed within a housing which is supported through oppositely extending trunnions journaled in the said longitudinal supports. 60

Another feature of the invention resides in the provision of self-aligning trunnions to the end that the several casings where supported may readily adapt themselves to movements of the chassis frame. 65

The important features of the construction will appear with greater particularity 70 hereinafter in connection with the detailed description of the embodiments shown in the accompanying drawings, wherein:

Figure 1 is a view showing in side elevation and somewhat conventionally the relative disposition of the propeller shaft and final drive of a motor vehicle to the side frame members of the chassis and one of the longitudinal supporting members on which the improved hoisting mechanism is supported. 75

Figure 2 is a view in transverse section through the chassis shown in Figure 1 and showing partly in elevation and partly in section the operating mechanism for two 80 lifting screws mounted in accordance with the invention.

Figure 3 is a view similar generally to Figure 2 but showing some modified details. 90

As the description proceeds it will be evident that the invention is not to be limited to the particular location in which it is used nor to the particular circumstances under which it may be useful although for the purposes of this application the mechanism is shown and will be described with reference to its mounting on the chassis of a motor vehicle propelled in a conventional manner through a longitudinally extending propeller shaft disposed under the chassis 100 and between the side frame members thereof. Referring to Figure 1 such a propeller shaft is indicated at *a* and the housing for the differential at the final drive by the reference character *b* and these parts are 105 disposed between two side frame members of the chassis indicated in Figure 2 at *c, d*. The physical objections to mounting a single cradle between the side frame members *c, d*, as proposed in the said co-pending applica- 110

tion will be understood since space is required for the extension of the propeller shaft *a*. Accordingly, one aspect of the present invention has to do with the mounting of the screw jacks *e*, *f*, in casings *e'*, *f'*, which are supported independently and are so spaced as to afford ample room therebetween for necessary parts of the vehicle such as the propeller shaft *a*. Other possible advantages from the improvements under some conditions of use will be pointed out more particularly hereinafter. Between the side frame members *c* and *d* are supported parallel beams *g*, *h*, which extend longitudinally for a sufficient distance to afford ample support for the respective housings *e'*, *f'*, respectively. These beams may be carried on cross-channels *g'*, *g''*, extending between the side frame members of the chassis, as will be evident. Formed with or secured to the opposite side walls of the casing *f'*, for instance, are trunnions *f''*, *f'''*, one of which *f''* is journaled in a bracket *d'* secured to the side frame member *d* and the other of which is journaled in the longitudinal support *h*. Within the housing *f'* is mounted a revoluble nut *i* through which extends the screw jack *f* and with which is engaged a drive pinion *k* keyed to the jack shaft *k'* all in the same general manner described in said co-pending application. The other housing *e'* is similarly mounted between the bracket *c'* on the other side frame member *c* and the other longitudinal support *a*. The jack shaft *k'* is rotated in one direction or another for raising or lifting the screw jacks by the clutch gear *l* which is splined thereon and engageable with one or the other of the gears *m* or *m'* which, themselves, are rotatable idly from any available source of power. All of the gears referred to may be mounted within a casing *n* which has formed therein or carries at opposite sides thereof trunnions *n'*, *n''*, journaled, respectively, in the longitudinal members *h*, *g*.

The extended wells *f''*, *e''*, formed at the bottoms of the respective casings *f'*, *e'* to receive the screw rods *f*, *e*, respectively, as seen in Figure 2, are spaced apart and at opposite sides of the differential housing *b* and propeller shaft *a*.

The construction described not only embodies all of the advantages of the principle pointed out in said co-pending case and the further advantage of providing clearance for the propeller shaft but, in addition, offers the further possible advantage that the two screw jacks are movable angularly with respect to one another so as to be relieved from stresses which might otherwise be imposed thereon as through weaving of the chassis frame or of the truck body.

Whereas in the embodiment shown in said co-pending case the screw rods are positively held in fixed relation to one another since they are mounted in a single cradle, in the present embodiment, they are not thus constrained and the angular position of one is wholly independent of the angular position of the other since the housings in which they are supported, respectively, move pivotally on their own trunnions.

The construction shown in Figure 3 does not differ essentially from that shown in Figure 2 except that it indicates permissible variations in design which will occur to those skilled in the art. Probably the most noticeable difference resides in the provision of hemispherical bearing surfaces *F²*, *F³*, *N'*, *N²*, on the several trunnions by means of which some degree of self-alignment is assured when the parts are assembled and, during use.

Other changes of design will occur to one skilled in the art but departures falling within the skill of a mechanic are not to be regarded as avoidance of the scope or spirit of the present invention as defined in the appended claims.

What we claim is:

1. In a motor vehicle, in combination with the chassis and propeller shaft extending longitudinally thereof, hoisting mechanism for a dump body mounted on the chassis comprising independent screw jacks disposed at opposite sides of the propeller shaft, revoluble nuts by which the jacks are raised and lowered, means to support the nuts on the chassis frame with capacity for angular movement of each, independent of the other, to conform to the angularity of the respective screws, and means mounted over the propeller shaft and carried by and between the nut supporting means for applying power to the nuts.

2. Hoisting mechanism for dump bodies including screw jacks disposed at opposite sides of the center line of the body, revolving nuts to actuate said jacks, respectively, supports extending in parallelism longitudinally of the chassis frame at opposite sides of the center line, casings in which said nuts are supported, means to mount the separate casings between the chassis frame members and said spaced supports, respectively, comprising trunnions mounted with capacity for independent movement and means carried by the supports and between the casings for applying power to the nuts.

This specification signed this 10th day of Sept., A. D. 1923.

JOSIAH E. REID.
CHARLES L. NEIN.
